[57] CLAIM

The ornamental design for an electric meter cover, as
shown and described.

DESCRIPTION

FIG. 1 is a perspective view of an electric meter cover
of my new design;

FIG. 2 is a front elevation of the electric meter cover;
FIG. 3 is a back elevation of the electric meter cover;
FIG. 4 is a side elevation of the electric meter cover, the
appearance of the other side being a mirror image
thereof;

FIG. 5 is a top plan of the electric meter cover; and,
FIG. 6 is a bottom plan of the electric meter cover.

FIG.1.

FIG.2.

FIG. 3

FIG. 4

FIG. 5.

FIG. 6.
